Fig. 4

Diagram illustrating the connections for ZRS, ZRS', TR, and MS'.

ZRS: The circuit starts with a common terminal 361. From 361, a line goes to 362, then to 343, 344, 345, 351, and 352. From 352, a line goes to 363, 364, 366, 365, 349, 348, 347, 369, 370, 371, 372, 368, 381, 373, 382, 369, 370, 371, 372, 362, 343, 344, 345, 351, 352, 361, and 360. From 360, a line goes to 378, 377, 375, 374, 379, 380, 386, 359, 363, 364, 366, 365, 349, 348, 347, 369, 370, 371, 372, 368, 381, 373, 382, 369, 370, 371, 372, 362, 343, 344, 345, 351, 352, 361, and 360.

ZRS': The circuit starts with a common terminal 360. From 360, a line goes to 378, 377, 375, 374, 379, 380, 386, 359, 363, 364, 366, 365, 349, 348, 347, 369, 370, 371, 372, 368, 381, 373, 382, 369, 370, 371, 372, 362, 343, 344, 345, 351, 352, 361, and 360.

TR: The circuit starts with a common terminal 360. From 360, a line goes to 355, 356, 357, 358, 359, 360, 361, 362, 363, 364, 365, 366, 349, 348, 347, 369, 370, 371, 372, 368, 381, 373, 382, 369, 370, 371, 372, 362, 343, 344, 345, 351, 352, 361, and 360.

MS': The circuit starts with a common terminal 360. From 360, a line goes to 355, 356, 357, 358, 359, 360, 361, 362, 363, 364, 365, 366, 349, 348, 347, 369, 370, 371, 372, 368, 381, 373, 382, 369, 370, 371, 372, 362, 343, 344, 345, 351, 352, 361, and 360.

UNITED STATES PATENT OFFICE

JOHN WICKS, OF OAK PARK, ILLINOIS, ASSIGNOR TO RESERVE HOLDING COMPANY, OF CHICAGO, ILLINOIS, A CORPORATION OF DELAWARE

ZONE METERING SYSTEM

Application filed June 3, 1929. Serial No. 367,996.

The present invention relates in general to zone metering telephone systems, but is particularly concerned with the provision of a zone metering system for use in conjunction with an automatic telephone system such as disclosed in the co-pending Wicks application, Serial No. 297,611, filed August 6, 1928.

The main object of the present invention is to provide zone metering equipment so designed that it may be readily installed at any time during or subsequent to the installation of the rest of the exchange.

The invention is disclosed in four sheets of drawings, which, when arranged with Fig. 1 placed to the left of Fig. 2, Fig. 3 below Fig. 2 with the corresponding conductors in alignment and with Fig. 4 to the immediate right of Fig. 3, show, by means of the usual circuit diagrams, a sufficient amount of equipment employed in a telephone system comprising the principles of the invention to enable the same to be understood.

Fig. 1 shows a first selector repeater SR, which is accessible to a lineswitch LS, associated with the line of a substation A. The lineswitch LS is of the well known rotary type, in which the wipers always remain upon the bank contacts last used. The selector repeater switch SR is of the well known vertical and rotary type. The circuits and apparatus of this figure are, in fact, quite similar to those disclosed in Fig. 3 of the co-pending application referred to, the selector-repeater SR having its circuits slightly modified in accordance with the invention.

Fig. 2 shows a plunger switch P, which is individual to the selector repeater SR, and is for associating the selector repeater with idle zone metering equipment when the selector-repeater is seized. The switch P is of the well known pre-selecting plunger type. A master switch MS, of well known type, functions to maintain the plunger of the switch P before bank contacts with which idle zone metering equipment is associated. Also shown in Fig. 2 are selector D, connector H, and called line equipment A', all of which may be like that disclosed in the co-pending application referred to, and are, therefore, only symbolically shown.

The equipment of Fig. 3 comprises a number of relays; for recording the zone to which a connection has been set up; for controlling the periodic assessment of a time lapse charge in accordance with the zone called; and for causing a zone charge to be made at the termination of a call unless terminated by an operator. Cooperating with these relays is a ten-point time limit switch TL, which is of the well known pawl and ratchet type provided with spring actuating means for restoring its wipers to normal position upon operation of its release magnet.

The switch TL cooperates with the other equipment of Fig. 3 to automatically break down the connection after the lapse of a fixed number of talking periods and also functions to stop the metering operation after an appropriate charge for the call has been made in case the call is terminated before the time limit has expired. Two rotary switches TPS and SPS of the same type as the lineswitch LS are also provided. The time pulse switch TPS is common to the exchange, and is continuously advanced under control of a time cam 249, which causes the wiper 281 of the switch to pass over all its contacts once every three minutes. The start pulse switch SPS functions to find the position of the wiper of switch TPS, the instant a call is answered, thereby establishing the period at which the charge is to begin.

In Fig. 4 is a zone register equipment comprising a zone register switch ZRS, which is mechanically like the selector repeater of Fig. 1. The switch ZRS is actuated by the first two series of impulses transmitted by a calling subscriber to determine the setting of the recording relays of Fig. 3, or to cause the release of all zone meter equipment if no charge is to be made for a connection to the zone called. A second zone register switch ZRS', which is mechanically of the same type as TL, in the right portion of Fig. 3, is actuated by the third series of impulses transmitted by the calling subscriber, and is provided to enable a third registration to be made when more than two digits are required to determine the zone. In the lower part of Fig. 4 is a time release switch TR, which

85

90

95

100

mechanically is of the same type as ZRS'. This switch and the zone register switches are associated with the equipment of Fig. 3 by a plunger switch P', similar to P, and is 5 one of a number of such switches each of which is permanently associated with a set of meter control equipment. The master switch MS' is identical to the master switch MS of Fig. 2 and has similar functions.

10 The purpose and character of the apparatus disclosed having been briefly described, a detailed description of its operation will now be given. For this purpose the operations which take place in setting up a 15 connection between the substations A and A' will first be explained.

Calls from substation A to substation A'

When the receiver is removed at substation A, a circuit is closed over line conductors 101 and 102 for line relay 104 of the line-switch LS. Line relay 104 energizes over the calling line and places ground on the associated private normal conductor 118 leading 20 to the banks of the connector switches having access to the line of substation A, thereby making this line busy to those connectors, and also closes a circuit through the combined switching and cut-off relay 103 and the motor magnet 105. Line relay 104 also 25 at armature 120 connects test wiper 111 through armature 107 and its resting contact to the junction of relay 103 and magnet 105. Accordingly, if the trunk upon 30 which the wipers of the switch are standing is busy the ground potential encountered by test wiper 111 shunts the relay 103 and prevents it from energizing and affords a direct 35 circuit for the self-interrupting stepping circuit for the stepping magnet 105. Accordingly, stepping magnet 40 105 operates in a buzzer-like manner to advance the wipers 110 to 113, inclusive, in search of an idle trunk line.

When an idle trunk line is reached, stepping magnet 105 ceases to operate, and relay 103, being no longer short circuited, energizes 45 in series with stepping magnet 105, which however, does not operate at this time on account of the relatively high resistance of 50 relay 103. Upon energizing, relay 103 disconnects test wiper 111 from the junction of 55 its own winding and that of magnet 105 and connects it to the grounded private normal conductor 118, thereby extending ground to the release trunk conductor 115 of the seized 60 trunk; it connects up the meter operating wiper 112 at armature 108; and at armatures 106 and 109 disconnects conductors 101 and 102 from line relay 104 and ground and extends them by way of wipers 110 and 113, 65 conductors 114 and 117, armatures 173 and 179 and their resting contacts, and through the upper and lower windings of line relay 121 and relay 124 to battery and ground. 70 Line relay 121 energizes over the above traced

circuit, but relay 124, being differential and stiffly adjusted, will operate only when ground is connected to both its windings. Line relay 121, upon energizing, at armature 75 140 closes a circuit for energizing relays 123 and 127 in series, and at armature 141 removes the short circuit from around release relay 122 and closes an energizing circuit for that relay in series with the vertical magnet 130 and the upper and lower windings of relay 126 80 in multiple. Release relay 122 energizes over the above traced circuit; the vertical magnet 130 does not operate because of the high resistance of release relay 122, while relay 126 does not operate because of the shunting effect of magnet 130. Release relay 122, upon energizing, at armature 142 closes a shunt around the armature 161 to prevent the circuit of relay 121 being opened by the energization of 85 relay 126; at armature 143 prepares a point in a holding circuit for relay 123; at armature 145 grounds the release trunk 115, thereby maintaining the lineswitch LS in operated position when ground is removed from armature 119 by the deenergization of line relay 104; at armature 146 grounds conductor 205; and at armature 147 completes a locking circuit for itself and prepares the impulsing 90 circuit for the vertical magnet 130. The circuit for energizing relays 123 and 127 may be traced as follows: from ground by way of the upper winding of relay 127, normally closed springs controlled by armature 180, normally closed springs controlled by armature 173, armature 140 and its working contact, and the upper windings of relays 123 and 124 in series to battery. Due to its spring 95 adjustment, and the current flowing in its lower winding, relay 124 is not energized over this circuit. Relay 123, upon energizing, at armature 149 opens a point in a circuit for the release magnet 19; and at armature 150 prepares an energizing circuit for relay 125, which, however, is open at armature 170 100 at this time. Relay 127, upon energizing, at armature 166 connects with ground through resistance 167, in order to maintain relay 123 energized during impulsing; at armature 168 and its working contact connects dial tone DT to conductor 114 notifying the subscriber to 105 begin dialling the called number; at armature 169 removes the shunt circuit from around the upper winding of relay 128; at armature 171 opens a point in an overflow 110 busy circuit; and at armature 170 opens a point in the circuit of relay 125 and at its working contact completes a locking circuit for itself, extending from ground by way of armature 150. This ground, it will be noted, 115 also extends by way of conductor 207 to the relay 210 in Fig. 2. This relay, therefore, operates and at armature 211 disconnects conductor 217 from the conductor 208 and connects it with conductor 204, and at its armature 212 completes an operating circuit ex- 120 125 130

tending through the contacts 214, the lower or pull-down winding 216 of switch P, and through the armature and resting contact of the master switch magnet 222 to battery. The 5 plunger of the switch P thereupon actuates and is held locked up over a circuit including its upper winding 227, the contacts 215, and the working contact and grounded armature 212 of relay 210.

10 By the operation of the plunger of switch P the selector of Fig. 1 is connected with the zone meter control equipment of Fig. 3. The closure of contacts 225 completes a holding circuit for the switch P which is independent 15 of relay 210. This circuit extends from battery, through the winding 227 of P, contacts 215, the bank contacts 225, conductor 220, the winding of relay 231, contact and armature 286 and the armature 287 and its grounded 20 contact. Relay 231 simply actuates to open a special impulsing circuit which will be traced later, and closes another point in the meter control circuit. The closure of bank contacts 224 of the switch P causes ground 25 on conductor 205 to be extended over conductor 219, through the armature 248 and its resting contact, to the winding of slow-release relay 234 and battery. The relay 234 operates, and at its armature 233 prepares an operating 30 circuit for relay 243, but this relay is prevented from operating at this time since it is short circuited by ground applied to the other terminal of its winding over the armature 248 and its resting contact; and at its armature 35 235 opens a second point in the circuit of the release magnet 330 of switch TL and applies ground to the holding conductor 320. A branch from this holding conductor passes over armature 257 and its resting contact to the winding of relay 260 and battery. Relay 40 260, upon operating, at its armature 263 closes a point in an automatic release circuit which will be described later, and at its armature 264 opens a point in a control circuit for the 45 meter. The ground supplied over conductor 219 also extends by way of armature 282 and its resting contact, conductor 341, through the break contacts 384 of the plunger switch P', its lower winding, and through the armature 50 and resting contact of the master switch control magnet 222' to battery. The switch P', therefore, also actuates, to extend the conductors 342-345, inclusive, to the zone register equipment of Fig. 4. In the operation of the 55 armature of switch P' the upper or holding winding 350 is substituted for the lower winding.

The closure of bank contact 354 of switch P' completes a third circuit from the grounded conductor 219, through the upper winding of relay 275, the armature 284 and its contact, conductor 343, bank contact 354, to the winding of slow release relay 347 and battery. The 60 resistance of relay 347 is made low enough to have sufficient shunting effect on relay 126 to

prevent the latter relay operating when the vertical magnet 130 is disconnected from the circuit. Relay 275 is marginal and does not operate in series with 347. The relay 347, however, operates, at its armature 348 opens a second point in the common circuit of release magnets 365, 386, and 392, at its front contact prepares a holding circuit for the relay 376, and at armature 349 completes a circuit for the operating magnet 391 of the timing release switch TR. This circuit extends from ground applied to the front contact of motor magnet 242 of switch TPS over the conductor 346, working contact and armature 349 and the winding of the magnet 391 to battery. This circuit is periodically closed by the constantly operating armature of magnet 242, which is included in a circuit with the constantly operating interrupter cam 249. As the ground impulses are transmitted over conductor 346 the switch TR steps its wipers over its bank contacts. 70 75 80 85

If the subscriber at substation A neglects to dial within the time required for the wipers 355 and 356 to be moved in connection with their fourth bank contact, the meter control equipment will be released and the calling subscriber given a busy signal. When the wiper 356 reaches position 4, battery is connected through the resistance 357 to the relay 275, increasing the current flow sufficiently to cause this relay to actuate. At the same time a ground impulse is transmitted to the operating magnet 391, ground potential now also passes over the wiper 355, through the off-normal springs 358, bank contacts 353, conductor 342, resting contact and armature 283, conductor 221, bank contacts 226 of switch P, and the conductor 206, and armature 183 and its resting contact to the vertical magnet 130 to battery. The selector repeater SR, therefore, takes one vertical step. The relay 275, upon operating, at its armature 286 interrupts the circuit of relay 231, permitting it to restore; at armature 276 applies ground potential from the grounded contact and armature 285 through the contact and armature 273 to the slow-release interrupter relay 251. This relay in turn, at its armature 265 completes a circuit for the slow-release relay 269, which operates and at its armature 271 transmits a ground pulse over the resting contact and armature 232, conductor 218, bank contacts 223, armature 211 and its working contact, conductor 204, and through the winding of the rotary magnet 131 to battery. The relays 251 and 269 now operate alternately to repeat pulses out over the conductor 218, causing the selector repeater SR to rotate its wipers until it is stopped by the operation of its cam springs 118 and 187 on the eleventh rotary step. The springs 118 in actuated position connect overflow busy tone to the calling line, and the springs 187 complete a circuit for relay 129. 90 95 100 105 110 115 120 125

at the termination of the eleventh impulse, from battery through magnet 131, through springs 187, the lower winding of 129 to ground on conductor 115. Relay 129 operates, at its armature 182 completes a shunt circuit about its upper winding rendering the relay slow to release and thereby preventing its release during the transmission of a subsequent impulse over conductor 204, and 5 at its contacts controlled by armature 180 interrupts the circuit of relays 123 and 127. Relay 127, upon restoring, at armature 170 opens the circuit of relay 210 of switch P. Relay 210 thereupon restores and interrupts 10 the holding circuit of switch P, which now restores. As a result of the restoration of switch P ground is removed from conductor 219, causing the relay 234 and switch P' to restore. The restoration of switch P' interrupts the circuit of relays 275 and 347 which 15 also restore. The relay 347, upon restoring, at its armature 348 completes the circuit of release magnet 392 of switch TR causing that switch to also restore to normal.

20 The calling subscriber, upon hearing the busy tone will replace his receiver, thereby bringing about the release of the selector repeater SR and line-switch LS, in a manner which will subsequently be made clear.

25 It will now be assumed that the subscriber initiates a call and begins dialling before the expiration of the time interval allowed. Responsive to the operation of the calling device, the loop circuit extending through line relay 121 is interrupted a plurality of 30 times, and said line relay falls back a corresponding number of times. Each time line relay 121 falls back, a circuit may be traced from ground by way of armature 147 and its contact, normally closed springs controlled 35 by armature 141, armature 183 and its resting contact, and through the winding of vertical magnet 130 to battery. By the operation of the vertical magnet 130 the switch wipers 190 to 192, inclusive, are operated opposite the 40 desired level of bank contacts. Branches of this impulsive circuit extend to the upper terminal of relay 126 and to conductor 206, respectively. Relay 121 at armature 141 also 45 closes a short circuit around release relay 122 in order to render the release relay slow to release, so that it will be maintained in operated position during the impulsive period; and at armature 140 closes a circuit for maintaining the relay 123 energized during pulsing. This circuit extends by way of ground through resistance 167 and armatures 166, 50 157, and 143, and their contacts, the springs controlled by armature 140, upper winding 55 of relays 123 and 124 in series to battery.

60 Relay 126 energizes upon the transmission of the first impulse, at armature 161 opens the initial energizing circuit for line relay 121; at armature 162 opens a point in a circuit 65 for the rotary magnet 131, so that the

rotary magnet will not operate when the off-normal springs 152 operate and close on the first vertical step of the switch and applies ground to release conductor 115 by way of armatures 178 and 153; and at armature 163 opens a point in the operating circuit of relay 125, and prepares a point in an auxiliary circuit for itself. Relay 126 remains operated during pulsing because it is made slightly slow to fall back when its circuit is 70 opened during the impulsive period because of the current flow through it and relay 122 in series at this time. However, after impulsive has ceased, relay 126 falls back, and at armature 162 closes a circuit for operating 75 the rotary magnet 131 as follows: from ground on release trunk conductor 115, armatures 153, 178, 162, 151 and their resting contacts, off-normal springs 152, resting contact and armature 181, interrupter springs 188 of 80 the rotary magnet 131, and the winding of said magnet to battery. By the operation of the rotary magnet, the switch wipers 190 to 192, inclusive, are rotated into engagement with the first set of bank contacts in the 85 selected level. Near the end of its stroke, rotary magnet 131 operates its interrupter springs 188, thereby interrupting its own circuit. The rotary magnet continues to 90 operate in a buzzer-like manner to step the wipers over the bank contacts in the selected level until the test wiper 191 encounters a 95 battery potential on one of the test contacts.

Assuming that the first idle trunk comprises the conductors 201 to 203, inclusive, 100 extending to the intermediate selector D shown in Fig. 2, then when wiper 191 encounters test contact 198 a circuit may be traced for energizing switching relay 129 as follows: ground by way of grounded conductor 205, armature 169 and its working contact, upper winding of switching relay 129, wiper 191, test contact 198, to conductor 105 202 which has battery supplied through a resistance 228 at selector D. Relay 129, upon 110 energizing, at armature 181 opens its rotary magnet circuit so as to stop the rotation of wipers 190—192, and closes a locking circuit for itself extending by way of the grounded conductor 115, its lower winding, its contact 115 and armature 181 and the winding of magnet 131 to battery; and closes a circuit from grounded conductor 205 through the upper winding of marginal relay 128 and through 120 working contact and armature 182 to the battery on wiper 191. Relay 128, being marginal, is not energized over this circuit, because of the resistance 228. The relay 129 also, at armature 183 opens a point in the 125 vertical magnet circuit and short circuits the upper winding of relay 126; and at its armatures 180 and 184 closes the controlling circuit of switch D. This circuit extends from battery through the upper windings of relays 124 and 123 in series, the working contact 120

and armature 140, springs controlled by armature 173, the working contact and armature 180, the wiper 190, bank contact 197 and conductor 201 to the selector D, and back over conductor 203, bank contact 199, armature 184 and its working contact, springs controlled by armature 179 and the lower windings of relays 123 and 124 in series to ground.

- 10 It will be recalled that relay 121, in transmitting impulses to the vertical magnet also transmitted impulses over conductor 206. This branch extends through the bank contacts 226 of switch P, conductor 221, armature 283 and its resting contact, conductor 342, bank contacts 353 of switch P', through the break springs 367, the winding of the slow release relay 369, and the vertical magnet 370 to battery. Upon the first vertical 15 step of the switch ZRS the formerly traced time release circuit is interrupted by the opening of off-normal springs 358; at off-normal springs 366 an operating circuit is prepared for the release magnet 365, while 20 at the off-normal springs 367 the impulsing circuit is slightly modified so that the subsequent impulses transmitted to the vertical magnet 370 pass through the armature and working contact of the slow-release relay 369. 25 At the termination of the first series of impulses, the slow release relay 369 restores its armature and, in so doing, prepares an operating circuit for the rotary magnet 378.

As the calling subscriber dials the remaining digits in the called number the line relay 121 of the switch SR operates in the same manner as during the transmission of the first digit. Each time the line relay de-energizes it interrupts the traced switch control circuit to the selector D, at the springs controlled by armature 140; and at armature 141 again completes the circuit of relay 126 as before.

Upon transmission of the second series of impulses, the impulses transmitted to the conductor 206 pass over the previously described path except that now they include the resting contact and armature of relay 369, slow release relay 375, the armature 377 and its resting contact and the winding of rotary magnet 378 to battery. The wipers 368 and 373, are, therefore, rotated into connection with contacts individual to the particular zone being called. The relay 375, which operates upon the transmission of the first impulse to the rotary magnet 378, at its armature 374, completes an operating circuit through the upper winding of two-step relay 376, which at this time merely actuates its armature 380, since its lower winding is short circuited by ground from the armature 348 and its working contact; and at its armatures 371 and 372 disconnects the wipers 368 and 373 from conductors 361 and 362 while passing over bank contacts. At the termina-

tion of the impulse series, however, the slow-release relay 375 removes ground from the midpoint of the winding of relay 376, permitting it to actuate the remainder of its contacts. The relay 376 at its armature 379, disconnects itself from the armature of relay 375, and at its armature 377 substitutes the operating magnet 385 of the switch ZRS' for the operating magnet 378. Upon the transmission of the third series of impulses, corresponding to the third digit of the called number, the operating magnet 385 of switch ZRS' actuates and positions its wipers 387 and 388 upon a set of contacts which determine the zone to which the connection has been extended, if such determination has not been already completed by the second digit of the called subscriber's number.

If the connection set up is one for which no charge is to be made, the wipers of the zone register switch ZRS will be connected with contacts marked X having direct ground potential thereon, causing zone recording relays 302, 310, 315, and 325 to all be operated upon the deenergization of relay 375. The circuits for relays 302 and 310 extend from battery through the upper windings of 302 and 310 in series, conductor 344, bank contacts 351, conductor 361, armature 372 and its resting contact, and the second lower bank contact of switch ZRS to ground. The relays 315 and 325 are energized over a circuit parallelizing the one just traced connecting with direct ground on the second lower bank contacts accessible to wiper 373.

When any of the relays 302, 310, 315, or 325 are operated, a circuit is completed through the lower winding of relay 280, which operates and at its armatures 282 interrupts the holding circuit of switch P', permitting it to restore; at armature 283 interrupts the circuit of relay 347; and at its armature 285 opens a point in the operating circuit of relay 251. Relay 347, upon restoring, at its armature 349 opens the operating circuit of magnet 391, and at its armature 348 applies ground to the release magnets of switches ZRS, ZRS' and TR, through their respective off-normal springs. The time and zone register switches are accordingly restored to normal and rendered available to other switches such as P'.

When all of the relays 302, 310, 315, and 325 are operated, as is the case under the circumstances assumed, a circuit is completed for the relay 275. This circuit extends from the grounded armature 235 and its working contact, conductor 320, armature 257 and its resting contact, armature 254 and its contact, armature 305 and its working contact, armature 313 and its working contact, armature 326 and its contact, and the lower winding of relay 275 to battery. The relay 275 operates and at its armature 286 opens the circuit of relay 231 and a point in a second holding cir-

cuit for the plunger lineswitch P of Fig. 2.

When the final digit of the called number has been transmitted, the connector H seizes the terminals of the line called, and, irrespective of the busy or idle condition of the line, a relay in the connector actuates to interrupt the loop extending back through the windings of relays 123 and 124. Relay 123 accordingly deenergizes, and at its armature

10 150 opens the locking circuit of relay 127, and the energizing circuit of relay 210. These relays accordingly deenergize. Relay 210, upon restoring opens the traced holding circuit of switch P, permitting it to restore.

15 The restoration of switch P causes the release of relay 234, as previously described. Relay 234, upon restoring at armature 235 interrupts the holding circuit of all operated relays in Fig. 3.

20 Relay 127, upon restoring, at its armature 168 closes a point in a path for the transmission of busy tone to the calling line, which is completed by the connector if the line called is busy. If the busy tone is received the calling subscriber replaces his receiver, thereby bringing about the release of the connection.

If the called line is idle, the response of the called subscriber causes a relay in the connector to again complete the circuit of relay 123 in the switch SR over the called subscriber's loop. Relay 123, upon energizing,

30 at armature 150 now completes an energizing circuit for the slow release relay 125, by way of armature 170 and its resting contact, the resting contact and armature 163, the winding of 125, the resting contact and armature 175, and off-normal springs 148 to battery, through the winding of magnet 19. Magnet 19 does not energize over this circuit due to the comparatively high resistance of 125.

40 Relay 125, upon operating, at armature 157 opens a point in the holding circuit of relay 123; at armature 158 completes a locking circuit for itself; at armature 159 prepares a locking circuit for relay 126; and at its armature 156 disconnects ground from conductor 208 and instead connects this conductor to meter conductor 116. Talking battery is now supplied to the calling subscriber through relays 121 and 124, and to the called subscriber through relays 123 and 124. Since the meter control apparatus has been disassociated from the connection no metering operation can take place.

55 If the substation A' is located in zone 1 with reference to substation A, the wipers 368 and 373 of the zone register switch ZRS will be positioned on their upper second, the upper ninth or lower tenth bank contacts, depending upon whether the zone is determined by two or three digits. It will be assumed that three digits were required and, therefore, of the relay group 302, 310, 315, and 325 a circuit including relays 302 and 310 is completed. This circuit extends from battery

through the windings of relays 302 and 310 in series, conductor 344, bank contacts 351, conductor 361, armature 372, conductor 382, wiper 368, the associated upper ninth bank contact, for example, conductor 389, wiper 388 and its third bank contact to ground through resistance 383. Owing to the marginal characteristic of relay 310 this relay is not operated at this time.

70 Relay 302, upon operating, at its armature 304 completes a holding circuit through its lower winding; at its armature 305 modifies the controlling circuit for the relay 277, which will be traced subsequently; at its armatures 306, 307, and 308 and their working contacts, closes points in the circuits extending from wipers 337, 251', 262, and 268, respectively, of the start pulse switch; and at armature 303 completes an operating circuit for relay 280. The relay 280, upon operating, at its armature 282, interrupts the formerly traced holding circuit through winding 350 of switch P', permitting that switch to restore. As a result of the restoration of the switch P' the switch mechanism 80 accessible thereto is restored to normal in the manner formerly described. The relay 280 also, at its armature 283 and its working contact substitutes its upper winding for that of relay 347 to prevent relay 126 operating 90 in series with the relay 122.

95 When the final digit of the called number has been transmitted and the connector H seizes the terminal of the line called, a relay in the connector actuates to interrupt 100 the loop circuit extending back through the windings of relays 123 and 124. Relay 123 accordingly deenergizes and at its armature 150 opens the locking circuit of relay 127, and the energizing circuit of relay 210. These 105 relays accordingly deenergize, as in the case of a call to a free line. The relay 210, upon restoring, at its armature 211 again connects conductor 217 with conductor 208, to prepare the meter circuit at this point; and disconnects its grounded armature from the holding circuit of switch P. The switch P does not restore, however, because of the presence of the formerly traced holding circuit 110 extended to the grounded contact of armature 287. Relay 127, upon restoring, at its armature 170 and its resting contact prepares an operating circuit for relay 125.

115 Upon the response of the called subscriber a relay in the connector H actuates to again 120 complete the loop circuit through relays 123 and 124. Relay 123, therefore, again energizes and completes the formerly traced circuit of relay 125. The relay 125, in addition to causing the previously described circuit changes, now causes the connected meter control equipment to be set into operation, by actuation of its armature 156. The removal 125 of ground potential from conductor 208 by the actuation of armature 156 permits the 130

two-step relay 237 to fully operate. This relay at its armature 268 closes another point in the meter control circuit; at its armature 239 opens a point in an operating circuit for relay 277 and closes a circuit for relay 256; at armature 241 closes a point in a controlling circuit including the wiper 274 of the start pulse switch SPS; and at its armature 240 completes a circuit for the motor magnet 335 of that switch. This latter circuit extends from grounded working contact and armature 240, to the resting contact and armature 291, and through the resting contact and armature and winding of motor magnet 335, to battery. The wipers of this switch are consequently rotated until ground potential, supplied by the wiper 281, of the time pulse switch is picked up by the wiper 274. It will be assumed that the wiper 281 of the time pulse switch TPS is positioned on its second bank contact when the wipers of the switch SPS encounter their sixth contact set. When this occurs, the ground potential on the next to bottom contact, supplied through wiper 281, passes over the wiper 274, through armature 241 and its contact, armature 292 and its resting contact, to the upper winding of relay 288 and battery. The relay 288 operates, at its armature 290 prepares an operating circuit for relay 295; at its armature 291 opens the operating circuit of magnet 335, thereby preventing further movement of the wipers of the switch SPS; and at the front contact of this armature completes the locking circuit for the relay 288, including the winding of the magnet 335, which will not operate in this circuit; and at armature 292 closes a point in an operating circuit for the relay 269 which will be traced subsequently. The wiper 281 continues to periodically step; when it arrives at the bank contact 1, ground is applied over the wiper 293, armature 290 and its working contact, through the springs controlled by armature 289, to the winding of relay 295 and battery. This relay thereupon operates, at its armature 289 completes a locking circuit for itself; at its armature 294 completes an operating circuit for the relay 250, and at its armature 296 prepares a circuit which is completed upon the next step of the switch TPS from the wiper 274 to the relay 269. This circuit extends from the said wiper, through armature 241 and its contact, armature 292 and its working contact, contact and armature 296, armature 306 and its contact, contact and armature 264, contact and armature 247, through the winding of relay 269 and battery. Relay 250, upon operating, completes a circuit from battery extending through the winding of motor magnet 329 of switch TL, conductor 334, contact and armature 253 to ground; at armature 279, causing that switch to advance its wipers 331 and 332 into engagement with their first contacts; at its armature 254 opens a point in an operating circuit for relay 277, and at its armature 255 interrupts the circuit of relay 256. Since the relay 256 is slow to release, ground potential is extended from the conductor 320, through armature 257 and its working contact, resistance 309, armature 252, conductor 221, bank contacts 226, conductor 206, to the relay 126. The current flow over this circuit causes relay 126 to pull up. This relay at its armature 161 and its working contact connects overflow busy tone through the contact and armature 142, and through the back contact and armature 173 to the calling subscriber. This tone, however, is applied momentarily only because the wiper 281 of switch TPS advances to its next contact, thereby interrupting the circuit of relay 250, which in turn causes the relay 126 to restore. The tone thus given serves to inform the calling subscriber that one talking period has practically been completed and that if he does not desire to be charged for a second talking period he must immediately restore the receiver.

The movement of the wiper 281 to its next bank contact causes ground to be extended over wiper 274 and the previously traced circuit to the slow release relay 269. This relay accordingly operates and at its armature 270 and its working contact transmits battery through the resistance 100, by way of the working contact and armature 268, working contact and armature 232, conductor 218, bank contacts 223, armature 211 and its resting contact, conductor 208, armature 156 and its working contact, meter conductor 116, wiper 112, armature 108 and its working contact, to the winding of the meter M and ground, thereby actuating the meter to charge for the first time period.

As the wiper 281 passes over its third to sixth bank contacts it also applies ground potential to the wipers 337, 268, 262, and 251, in sequence. Since, however, in the present connection only the wiper 274 is connected through to the relay 269 the relay 269 will only operate once. When the wiper 281 encounters the sixth contact ground will again be transmitted to the relay 250 to again advance the wipers of switch TL, and cause the tone to be again temporarily connected out over the calling line to apprise the calling subscriber that a third time charge period is about to begin.

It will be assumed that the conversation is now terminated.

The replacement of the called subscriber's receiver causes relay 123 to deenergize and at its armature 149 close a point in the circuit of release magnet 19.

When the calling subscriber replaces his receiver, line relay 121 releases, and at armature 141 completes a short circuit around the winding of relay 122, thereby rendering it slow to release. Before the release of relay 122

122, a circuit is now completed for relay 126, by way of grounded armature 147 and its working contact, and the springs controlled by armature 141. Relay 126, upon operating, at armature 161 opens a second point in the circuit of relay 121, at armature 162 connects ground, by way of armatures 178 and 153, to the release trunk 115 to maintain the switch LS operated during the metering operation; and at armature 163 completes a locking circuit for itself independent of relay 122. This circuit extends from armature 158, through armature 163 and its working contact, armature 159, and the springs controlled by armature 141. After an interval relay 122 releases, and at its armature 142 opens another point in the circuit of line relay 121, so that the calling subscriber cannot interfere with the metering operation by again removing his receiver; at armature 145 removes one of the ground connections from the release conductor 115; and at its armature 146 removes ground from conductor 205, thereby removing the short circuit from about relay 243 of Fig. 3. The relay 243, therefore, now operates, at its armature 248 reconnects ground potential over 219, 224, and 205 to prevent the deenergization of relays 125 and 126; at armature 244 prepares an operating circuit for relay 277, which is independent of armatures 254; at armature 245 prepares an operating circuit for relay 251; at armature 246 opens the circuit of relay 256, and before this relay restores, completes a circuit, by way of armatures 246 and 258, for the release magnet 330 of switch TL, causing its wipers 331 and 332 to restore. Relay 256, upon restoring, at its armature 261 again prepares another operating circuit for the motor magnet 329 of switch TL; at armature 259 opens a point in an automatic release control circuit, which will be described later; at armature 258 opens a second point in the circuit of release magnet 330; and at armature 257 completes operating circuits for relays 260 and 251. The circuit for relay 260 extends direct from the resting contact of armature 257, while that of relay 251 extends by way of armatures 257, 245, and 273. The operation of relay 260 is without effect at this time, since the circuits controlled by its armatures are already open at armatures 259 and 247. The relay 251, upon operating, at its armature 266 completes an operating circuit for motor magnet 329 of switch TL by way of armature 261 and conductor 334 causing it to advance its wipers into engagement with their first contacts; and at armature 265 completes an operating circuit for relay 269. Relay 269, upon operating, at armature 270 connects battery through resistance 100, and over the previously traced circuit to meter M, causing the meter to again actuate; and at armature 273 interrupts the circuit of relay 251. Relay

251 thereupon restores and again opens the circuit of relay 269. Obviously if nothing happens to prevent it, these relays will continue to operate alternately.

Since, however, the connection under consideration was established to a line in zone 1 the movement of wiper 332 into engagement with its first bank contact, completes a circuit for cut-off relay 277. This circuit extends from battery through the winding of 70 277, wiper 332 and its first bank contact, resting contact and armature 318, resting contact and armature 313, working contact and armature 305, armature 244 and its working contact, and the resting contact and armature 257 to the grounded conductor 320. The relay 277, upon operating, at its armature 279 removes ground from the holding circuit of 75 relays 234, 243, 126 and 125; at its armature 278 locks up from ground on conductor 320; and at armature 287 interrupts the series circuit including relay 231 and the holding winding 227 of switch P. The switch P, upon 80 restoring, at springs 213 completes the circuit of release magnet 19 of the selector repeater SR causing that switch to restore. This circuit extends from the grounded resting contact and armature 156, conductor 208, 85 springs 213, conductor 209, armatures 144, 149, and 175 and off-normal springs 148 to the 90 release magnet and battery.

Had the connection been established to zone 5, the wipers 368 and 373 of the zone switch ZRS would have been positioned on contacts such as those marked Z5, resulting 100 in the energization of relays 302 and 315. With these two relays operated wipers 251, 262, 268, 274 and 337 are connected to meter control conductor 340 and therefore, each 105 time the wiper 281 of switch TPS passes over the first to sixth contacts a series of five impulses will be transmitted to the meter M. Also following the termination of the call relay 269 will actuate five times before being cut off by the energization of relay 277 which now has its circuit completed through the fifth bank contact of switch TL, working contact and armature 318, resting contact and armature 313 and the working contact and armature 305.

If the conversation has not terminated at the end of the fourth time period it will be automatically terminated as the wiper 331 encounters its fourth bank contact. This is brought about by the momentary closure of 110 a circuit for operating relay 126 and for short circuiting the slow-release relay 122 of the selector repeater by supplying ground from the grounded resting contact and armature 279, through armature 253 and its resting contact, wiper 331, conductor 336, armature 263 and its contact, armature 259 and its contact, conductor 221 and over the 115 previously traced circuit to conductor 206 leading to the upper terminal of relay 122. 120 125 130

This relay in restoring causes the zone metering equipment to function in the same manner as when the calling subscriber replaced his receiver.

5 As previously stated the instant invention is designed for use in a telephone system such as disclosed in the co-pending Wicks application, Serial No. 297,611, filed August 6, 1928. The selector repeater SR, like the one disclosed in the foregoing application, may be released by a toll operator when such operator desires to complete a toll call to either station A or A'.

If the operator wishes to complete a toll 15 call to station A', she sets up a connection to such station, and by operating a key may converse with the subscriber at station A'. If she desires to break down the local connection she may do so by again operating the 20 key. This causes circuit changes to occur which result in the grounding of normal conductors 297 and 299 of station A' which extend back to and through the differential relay 124 of switch SR causing that relay to 25 energize, as fully described in the co-pending application referred to. Relay 124, upon energizing, at armature 154 closes an energizing circuit for relay 128; at armature 153 opens a point in the circuit to the rotary 30 magnet 131, and closes an energizing circuit for the release magnet 19 from the grounded release trunk conductor 115, thereby causing the first selector repeater SR to release. Relay 128, upon energizing, at armatures 173 35 and 179 opens the circuits of relays 121-123, and 124; at armature 175 it opens the circuit of relay 125, permitting that relay to restore and prevent further metering; at armature 176 completes a locking circuit for itself by 40 way of the grounded release trunk conductor 115; and at armature 178 momentarily grounds the wiper 191. The relay 128 also, at its armatures 173 and 179, cuts the talking conductors straight through. This latter 45 operation is of no utility so far as the present invention is concerned, but is the usual arrangement provided for enabling the switch SR to seize an operator's trunk, or a ring-back switch for enabling calls being made 50 back on a calling party line. It should be understood that on such calls the test wiper encounters direct battery, thereby enabling the relay 128 to operate in multiple with relay 129 upon the operation of armature 182. 55 Line relay 121, upon deenergizing, at armature 141 opens the circuit of the release relay 122. Relay 124, upon deenergizing, at armature 153 closes the release magnet circuit, and at armature 154 opens the initial energizing circuit of relay 128. After an interval 60 relay 122 deenergizes thereby bringing about the operation and release of the meter control equipment in the same manner as in former examples. However, since in the 65 present case relay 125 is deenergized no

charge is made for an incomplete talking period interrupted by an operator.

The lineswitch of station A' (not shown) is prevented from being released by the release of the connection with line A, by ground potential supplied to it by the connector of the toll switch train. 70

If the operator wishes to set up a toll connection to station A, instead of A', she causes the line normals 101, 102, and 118 to be seized 75 by the connector of the toll switch train. The operator, as in the case when station A' was called, causes ground potential to be applied to the called line normals. Ground potential applied to conductor 118 prevents the release 80 of line switch LS upon the deenergization of relay 122. The application of ground potential to the normal conductor 102 effectively short circuits the lower windings of relays 121 and 124, and, therefore, the application 85 of ground potential to conductor 101 directly through the upper windings of relays 121 and 124 causes relay 124 to operate. This relay, upon operating, causes the switch SR to release, as before, but in this case relays 128 and 90 129 are held energized by the ground potential on conductor 118. Relay 128 is held energized in order to disconnect battery and ground in the selector repeater SR from the line of station A. As in the former case, the 95 meter control equipment is prevented from causing further actuations of the calling line meter owing to the deenergized condition of relay 125.

What is claimed is:

1. In a telephone system, a calling line, switches available to said line for use in extending connections to called lines, a meter associated with the calling line, meter control equipment common to said switches, means responsive to the seizure of one of said switches for automatically associating said switch with said meter control equipment, means in said meter control equipment operable incidental to the establishment of a connection to determine the minimum charge to be made for the call, means also included in said equipment for making a corresponding charge at the termination of a predetermined time period after a call has been answered and periodically thereafter, and means operative responsive to the termination of the call for causing said minimum charge to also be made. 105 110 115

2. In a telephone system, a calling line 120 equipped with a meter, a called line, a train of automatic switches for completing a connection between said lines, a circuit for operating said meter, and means operated upon the response of the called subscriber to prepare said circuit and to cause said meter to be periodically operated during the existence of a talking connection and for also causing the operation of the meter after the termination of a talking connection. 125 130

3. In a telephone system, calling and called lines, a meter for the calling line, means including a series of subscriber controlled automatic switches for establishing a connection 5 between said lines, zone metering equipment normally disassociated from said switches, other control equipment normally disassociated from the said switches and from said zone metering equipment, means responsive 10 to the seizure of one of said switches for associating said zone metering equipment therewith, and means responsive to such connection to associate said other control equipment with said switch.
4. In a telephone system, a calling line, a meter for said line, a series of subscriber controlled switches for setting up a talking connection to a called line, zone recording and 15 time and zone metering apparatus, means responsive to the seizure of the first of said switches to connect it with said apparatus, zone register equipment available to said apparatus, and means responsive to the seizure of said zone metering apparatus for 20 causing the seizure by it of the zone registering apparatus.
5. In a telephone system, calling and called lines, subscriber controlled switches for setting up connections between said lines, zone 25 register switches operable consequent to the operation of certain of said first-mentioned switches, relays controlled by said zone register switches in a manner characteristic of the zone called, and means responsive to the 30 operation of any one of said relays for causing the disassociation of the zone register switches therefrom.
6. In a telephone system, calling and called lines, subscriber controlled switches for setting up connections between said lines, zone 35 register switches operable consequent to the operation of certain of said first-mentioned switches, relays controlled by said zone register switches in a manner characteristic of the zone called, means responsive to the operation 40 of any one of said relays for causing the disassociation of the zone register switches therefrom, and other apparatus subsequently controlled to charge for the connection at a 45 rate dependent on which of said relays are operated.
7. In a measured service telephone system, a calling line in one exchange, a called line in a second exchange, electro-mechanical 50 means for establishing a talking connection between said lines, a meter for the calling line, means responsive to the setting up of a connection for determining the minimum 55 number of times the meter of the calling line will be operated at the termination of the call if the called subscriber responds, means for then automatically disassociating said determining means from the connection, and means for causing the meter to also be operated 60 periodically such a predetermined number 65

ber of times prior to the termination of the call for each set period the connection is maintained.

8. In a measured service telephone system, a calling and a called line, a subscriber controlled switch seizable by the calling line to set up a connection in the direction of the called line, an impulsing relay, and means for causing said relay to automatically transmit impulses to operate said switch to notify the subscriber that he has failed to operate it within a predetermined time and that he must therefore replace his receiver and reinitiate the call.

9. In a measured service telephone system, a calling and a called line, a subscriber controlled switch seizable by the calling line to set up a connection in the direction of the called line, an impulsing relay, means for causing said relay to automatically transmit impulses to operate said switch to notify the subscriber that he has failed to operate it within a predetermined time and that he must therefore replace his receiver and reinitiate the call, and means for causing said relay to transmit impulses to charge for the connection in case the same is completed and the called party responds.

10. In a telephone system, a calling line, an automatic switch operable by impulses transmitted from said calling line to extend a connection in the direction of a called line, means responsive to the removal of the receiver at the station of said calling line for seizing said switch, and means operative to automatically disassociate said switch control by impulses transmitted from the calling line if the subscriber fails to transmit impulses to the switch within a predetermined time.

11. In a telephone system, a switch, a calling line having means associated therewith, responsive to the removal of the receiver at the substation thereof, to extend a connection to said switch, means for transmitting impulses over the calling line to actuate said switch in the direction of a called line, and means for automatically transmitting impulses to actuate said switch to notify the subscriber that he has failed to cause its operation within a predetermined time.

12. In a telephone system, a calling and a called line, a meter associated with the calling line, a series of automatic switches included in an established connection between said lines, meter control equipment associated with the connection, means for causing said meter control equipment to operate the calling line meter prior to the termination of the connection, means responsive to the termination of the connection by replacement of the receiver at the calling station for causing the meter control equipment to also actuate the meter and the connection to be released and means in one of said switches, alternatively operative responsive to the

seizure of one of said lines prior to the replacement of the receiver at the calling station, to release the connection and prevent further operation of said meter.

- 5 13. In an automatic telephone system, a calling line, a called line, a meter for the calling line, zone and lapse time meter control equipment, means for causing said equipment to function and cause the operation of 70
10 said meter a number of times at the expiration of each definite time interval of the talking connection, and means for automatically interrupting the talking connection at the expiration of a certain time interval, simultaneously stopping the lapse time metering 75
15 operation, operating the meter a number of times dependent on the zone called and for then releasing the meter control equipment and the connection.
- 20 14. In a telephone system, a calling line, a meter for said line, a series of automatic switches for establishing connections from said line to called lines, meter control equipment divided into two units, means for associating both units of said meter control equipment with a certain switch of said series when such switch is seized, means for operating said equipment during the progress of the establishment of a connection to determine 80
25 the rate of charge to be made for the connection, means for then automatically disassociating one of said units from the connection, and means for causing the other unit to automatically disassociate itself from the connection if there is no charge to be made therefor.
- 30 15. In a telephone system, a calling line, switches available to said line for use in extending connections to called lines, a meter associated with the calling line, equipment 85
35 common to said switches for controlling the meter after a connection is set up, and means responsive to the seizure of one of said switches for automatically associating the seized switch with said control equipment.
- 40 16. In a telephone system, a calling line, switches available to said line for use in extending connections to called lines, a meter associated with the calling line, meter control equipment, common to said switches, 90
45 means responsive to the seizure of one of said switches for automatically associating such switch with said meter control equipment, means in said meter control equipment operable incidental to the establishment 95
50 of the connection for determining the rate of charge for the call, and means for immediately thereafter automatically disassociating said last means of the meter control equipment from the connection.
- 55 17. In a telephone system, a calling line equipped with a meter, means including one of a plurality of automatic switches for extending a connection to a called line, means associated with the connection set in motion 100
60 consequent to the response of a called party.

to actuate the meter periodically throughout the talking period and also thereafter, an automatic switch, means for actuating said switch to limit the talking period, and means for then actuating said switch to bring about 70
75 the release of the connection as soon as the meter has been operated the required number of times subsequent to the termination of the talking period.

18. In a telephone system, a calling line 75
equipped with a meter, means including any one of a plurality of automatic switches 80
seizable consequent to the removal of the receiver of the calling line for extending a connection in the direction of a called line, means common to said switches associated with the connection throughout its duration for actuating said meter, and means temporarily associated with the connection operative while the connection is being set up to 85
85 prepare said last means for operation in accordance with the destination of the call.

19. In a telephone system, a calling line equipped with a meter, switches available to said line for extending connections to called lines, a plurality of meter actuating means common to said switches, means responsive to the seizure of one of said switches for automatically associating the seized switch with one of said meter actuating means, a plurality 90
95 of other means common to said switches and to said meter actuating means for setting the seized meter actuating means in accordance with the destination of the call, and means automatically operated consequent to 100
100 the seizure of one of said meter actuating means for seizing one of said setting means.

In witness whereof, I hereunto subscribe my name this 31st day of May, A. D. 1929.
